AUTOMATIC VENTILATOR CLOSING DEVICE
Hobart E. Machamer, Oak Park, Ill., assignor to Ceco
Steel Products Corporation, Chicago, Ill., a corporation
of Delaware

Filed Dec. 26, 1961, Ser. No. 161,815
13 Claims. (Cl. 189—71)

The present invention relates to a ventilator or window closing device and more particularly to such a device for automatically and positively closing a lot line ventilating window for effectively protecting against combustion occurring adjacent to such a ventilator of a building.

Such ventilator assembly consists of a fixed metal frame with a metal ventilator swingably or pivotally mounted and retained opened for ventilation purposes, and the present invention is intended to provide means for positively closing the ventilating portion of the window should a fire occur on adjacent property to thus prevent danger from combustion through the open ventilator. To prevent such danger, the present novel assembly provides a device to close the ventilator automatically when the temperature thereat reaches a predetermined level.

Among the objects of the present invention is the provision of a novel tensioning means so constructed and arranged and of sufficient strength to overcome the holding effort applied to a projected or pivoted ventilator to force the ventilator shut and hold it in closed position whenever it is subjected to an elevated temperature.

Such means embodies a contractile spring held under tension and positively and automatically released when the ambient temperature at the open ventilator reaches a predetermined value.

Another object of the present invention is the provision in the novel ventilator closing means of a fusible link which separates when the temperature rises to the melting point of the fusible portion of the link. One end of the link is connected to the base channel or frame of the window and the opposite end has an eyelet or loop which is engaged by a hooked end of the spring placed under tension. The opposite end of the spring is anchored to the base channel or frame of the window in spaced relation to the link.

In the novel embodiment, the replaceable fusible link retains a spring under tension until affected by the elevated temperature to which it is subjected. Subsequently, a new link may be easily attached to the spring and the window frame to again place and retain the spring under tension and reset the automatic closing device.

The present invention further comprehends the provision of a second relatively light spring within the first spring connected to the ventilator frame through a length of cable. This second spring is of insufficient strength to close or slam the ventilator shut, but is principally utilized to keep the cable taut. The cable is of such a length that when the ventilator is opened a prescribed amount, an eyelet on the inner end of the cable abuts and is stopped by the reduced spiral end of the larger spring under tension.

The present invention also comprehends the provision of latch means on the lower rail or sill of the ventilator adapted to engage a strike on the sill or meeting rail of the encompassing stationary frame to lock the ventilator when it is slammed shut by the closing device. However, the tensioned contractile spring is of such strength as to effectively retain the ventilator closed without the aid of additional locking means.

Further objects are to provide a construction of maximum simplicity, efficiency, economy and ease of assembly and operation, and such further objects, advan-

2

tages and capabilities as will later more fully appear and are inherently possessed thereby.

In the drawings:

FIG. 1 is a perspective view of a typical installation of the automatic closing device attached to a ventilator and its frame, the view being taken from the outside of the window.

FIG. 2 is an enlarged fragmentary vertical cross-sectional view taken on the line 2—2 of FIG. 5 and showing the lower rail or sill of the ventilator and the frame sill or meeting rail with the ventilator in open position.

FIG. 3 is an enlarged fragmentary vertical cross-sectional view taken on the line 3—3 of FIG. 4 and showing the ventilator in closed position.

FIG. 4 is a vertical cross-sectional view taken on the line 4—4 of FIG. 3 and showing the interior of the closing device and the position of the springs when the ventilator is closed, the cover therefor having been removed.

FIG. 5 is a vertical cross-sectional view taken on the line 5—5 of FIG. 2 and viewed in the direction of the arrows showing the position of the springs when the ventilator is open.

FIG. 6 is a fragmentary horizontal cross-sectional view showing the component parts of the closing device at one end thereof including the fusible link and its operative position in the device.

FIG. 7 is a top plan view of the closing device with a portion of the cover broken away and showing the device when the fusible link has separated and the ventilating window has been forced or slammed shut.

Referring to the disclosure in the drawings wherein is shown a novel illustrative embodiment of the present automatic ventilator closing device, FIG. 1 discloses a ventilator 10 pivotally mounted within a stationary frame 11 where the ventilator is pivoted adjacent the top of the frame and has supporting bars 12 aiding in positioning the ventilator in open position. An automatic closing device 13 is shown secured to the sill or meeting rail 14 of the window frame 11 and connected to the ventilator 10 through a cable 15, preferably formed of stainless steel, and of such a length that the ventilator 10 may be opened and retained open a prescribed amount, for example, an opening of approximately four inches.

The cable 15 terminates in each end in an eyelet 16 having a shank portion 17 which is clinched to the cable. An L-shaped pin 18 is suitably affixed or screwed into the bottom rail of the ventilator 10 (FIGS. 2 and 3) and one eyelet 16 is slipped over the pin. The opposite eyelet 16 is connected to the hooked end 19 of a relatively light spring 21; the opposite end of the spring 21 having a hooked end 22 connected to the base 23 of the closing device 13 through an anchoring projection or tab 24 formed in the base 23.

The base 23 is secured to the sill, meeting rail or base channel 14 of the window frame 11 by a pair of screws or other suitable attaching means 25. A spindle 26 is rotatably mounted on one of the attaching screws 25 with the spindle acting as a guide for and over which the cable 15 passes. The cable normally remains attached to the ventilator 10 although one end thereof may be manually removed from the pin 18 permitting opening the ventilator 10 a full 90° for washing the outside of the transparency from within the building.

A larger and stronger contractile spring 27, designed to assure forcing or slamming the window shut, has one end formed into a hook 28 which is also secured to the anchoring projection or tab 24. The opposite hooked end 29 of the spring 27 is attached to one end of a heat fusible and separable link 31 by means of an eyelet 32 formed in the link. The opposite end of the link is also

formed as an eyelet 33 which is hooked over a second anchoring projection or tab 34 formed in the base 23 of the closing device 13. The link 31 is formed of separable sections 35, 35^a which are held together by interlocking tabs 36 of metal that melts at a relatively low temperature, e.g. approximately 160° F. A removable cover 37 for the closing device 13 is snapped into place upon the base 23. This cover has openings 38 (FIG. 7) which expose the fusible link 31.

In operation, the cable 15 and its connected spring 21 move within the larger contractile spring 27 which is placed under tension by connecting the link 31 to the tab 34 (see FIGS. 4, 5 and 6). The smaller spring 21 does not have sufficient strength to retract the ventilator 10 when open. FIG. 4 shows the relative positions of the cable 15 and the two springs 21 and 27 with the ventilator 10 closed. When the ventilator 10 is opened (FIGS. 2 and 5), the cable 15 which passes over the spindle 26 extends the spring 21 until the eyelet 16 abuts the adjacent reduced end coil of the larger spring 27, thus limiting the extent of opening movement of the ventilator 10 (see FIGS. 5 and 6). The spring 21 is used principally to keep the cable 15 taut.

If the ambient temperature adjacent the window rises to approximately 160° F., due to combustion, the fusible link 31 separates into the two sections 35, 35^a releasing the larger spring 27, and the contractile spring 27 retracts carrying with it the eyelet 16 and the cable 15 to force or slam the ventilator shut. While the spring 27 will exert sufficient force to hold the ventilator tightly closed, a conventional cam action type locking handle 39 (FIG. 2) may be used in conjunction with a strike 41 on the base or meeting rail 14 of the window frame 11, or a conventional spring latch 42 (FIG. 3) may be utilized for this purpose.

It is obvious that the positioning of the automatic closing device 13 can be reversed and mounted upon the frame of the pivoted ventilator 10 with the cable 15 extending from the closing device connected by suitable means to the stationary window frame 11, and such arrangement is contemplated by the present invention and claims.

Having thus disclosed the invention, I claim:

1. An automatic closing device for a ventilating window including a stationary frame and a ventilator swingably mounted in said frame, comprising a cable connected at one end to the ventilator, a relatively light contractile spring connected at one end to said cable and at its other end anchored to the frame, a relatively heavy contractile spring anchored at one end to said frame, a fusible link anchored at one end to said frame and at its other end connected to the other end of said relatively heavy contractile spring, said relatively light and heavy contractile springs being so constructed and arranged that when said fusible link is subjected to an elevated temperature the parts of said link separate and release one end of the relatively heavy contractile spring to release the tension on the latter whereupon the relatively light contractile spring and its connected cable are retracted to forcibly close the ventilator.

2. An automatic closing device as set forth in claim 1, in which the relatively heavy contractile spring is held under tension and the relatively light contractile spring is placed under tension when the ventilator is opened.

3. An automatic closing device as set forth in claim 1, in which the relatively heavy contractile spring is held under tension and the relatively light contractile spring is placed under tension when the ventilator is opened, the relatively light contractile spring being arranged within the relatively heavy contractile spring and the latter limits the extension of the lighter spring.

4. An automatic closing device for a ventilating window assembly including relatively movable members one of which is a stationary frame and the other a ventilator swingably mounted in said frame, comprising a cable

connected at one end to one of said members, a relatively light contractile spring connected at one end to said cable and at its other end anchored to the other of said members, a relatively heavy contractile spring anchored at one end to the other of said members, a fusible link anchored at one end to said other member and at its other end connected to the other end of said relatively heavy contractile spring, said relatively light and heavy contractile springs being so constructed and arranged that when said fusible link is subjected to an elevated temperature the parts of said link separate and release one end of the relatively heavy contractile spring to release the tension on the latter whereupon the relatively light contractile spring and its connected cable are retracted to forcibly close the ventilator.

5. Means for positively and automatically closing a ventilating window member swingably mounted in a stationary frame member, comprising a closing device including a base mounted on one of said members, a pair of contractile springs each having one end affixed to said base, one of said contractile springs being relatively light and connected at its other end to the other member and placed under tension when the ventilator is opened, said other contractile spring being relatively heavy, a separable fusible link anchored at one end to said base and connected at its other end to the other end of said relatively heavy contractile spring and retaining said last mentioned spring under tension until said fusible link separates when subjected to an elevated temperature, whereupon said last mentioned spring automatically closes said ventilating window member.

6. Means for positively and automatically closing a ventilating window member swingably mounted in a stationary frame member as set forth in claim 5, in which said closing device is mounted on the meeting rail of said stationary frame member and a cable connects the relatively light contractile spring to the ventilating member.

7. Means for positively and automatically closing a ventilating window member swingably mounted in a stationary frame member as set forth in claim 5, in which said closing device is mounted on the meeting rail of said stationary frame member and a cable connects the relatively light contractile spring to the ventilating member, said relatively light contractile spring being enclosed within the relatively heavy contractile spring and when the fusible link is separated, the latter spring contracts and carries therewith the lighter spring and forcibly closes the ventilating member.

8. An automatic closing device for a window including a stationary frame and a ventilator swingably mounted in the frame, comprising a base for the closing device secured to the frame, a spindle mounted adjacent one end of the base, a cable passing over the spindle and terminating at each end in an eyelet, one eyelet attached to the ventilator, a spring attached at one end to the other eyelet on the cable and its other end to said base, a second relatively stronger spring encompassing the first mentioned spring and the last mentioned eyelet on said cable secured at one end to said base, a fusible link separable into two portions and connected at one end to said base adjacent said spindle, and the free end of said stronger spring being connected to the opposite end of said link, said link adapted to separate and release said stronger spring to retract said ventilator when the ambient temperature reaches a predetermined level.

9. An automatic closing device for a ventilating window having a fixed frame and a pivoted ventilator adapted to swing out, comprising a support affixed to said frame, a cable detachably connected at one end to said ventilator, a contractile spring connected at one end to the opposite end of said cable and the other end of the spring attached to the support, said spring retaining the cable taut but not of sufficient strength to retract said ventilator, heat separable means connected at one end to the support, and a relatively strong spring normally extended under tension

and connected to said heat separable means and the opposite end of said support, said cable and attached spring passing through said relatively strong spring such that when said heat separable means separates at a predetermined temperature said relatively strong spring retracts carrying the cable therewith to forcibly close the ventilator.

10. An automatic closing device for a ventilating window having a fixed frame and a ventilator swingably mounted in said frame, comprising heat separable means anchored at one end to the frame, an anchoring projection spaced from said heat separable means on said frame, a relatively strong spring under tension and extending between said heat separable means and said anchoring projection, a cable connected at one end to the ventilator and resiliently connected at its opposite end to said anchoring projection, one end of said cable passing through said spring, and an eyelet on the end of said cable coacting with said spring to limit movement of said cable and opening of said ventilator, said heat separable means when subjected to an elevated temperature releasing said spring to rapidly and positively close said ventilator.

11. An automatic closing device for a ventilator pivotally mounted in a fixed frame, comprising heat releasable means attached at one end to the ventilator frame adjacent one end thereof, relatively strong resilient means tensioned between said releasable means and an anchoring projection on the opposite end of said frame, and a cable connected at one end to the ventilator and at the other end connected to one end of a contractile spring with the other end of the spring connected to said opposite end of said frame permitting limited opening of the ventilator under tension, said cable having an eyelet located within and engaged by said resilient means whereupon said releasable means releases said resilient means

35

when subjected to an elevated temperature to retract said cable and forcibly close the ventilator.

12. An automatic closing device for a ventilator pivotally mounted in a stationary frame, comprising fusible means secured at one end adjacent one end of the ventilator frame, a contractile spring connected to the other end of said fusible means and to the opposite end of the frame, said spring normally being under tension until released when said fusible means is subjected to heat at an elevated temperature, a cable movable through and relative to said spring and resiliently connected between the opposite end of the frame and the ventilator, and means on said cable coacting with an end of said spring to limit movement of said cable in opening of the ventilator and to positively retract said cable and ventilator when said fusible means releases said spring.

13. An automatic closing device for a ventilator swingably mounted in a frame, comprising a separable, fusible link attached at one end to the frame, a relatively strong contractile spring connected at one end to said fusible link and at its other end to the frame and thereby held under tension, a cable resiliently mounted at one end to the frame and extending through said spring and connected at its opposite end to the lower rail of the ventilator, guide means adjacent said fusible link for said cable, and an enlarged portion on said cable within said spring for limiting travel of said cable and the extent of opening the ventilator and retracting the cable when the spring is released upon separation of the fusible link when subjected to an elevated temperature.
